UNITED STATES PATENT OFFICE.

WILLIAM L. CHURCHILL, OF CHICAGO, ILLINOIS, ASSIGNOR TO NATIONAL PNEUMATIC SERVICE COMPANY, OF CHICAGO, ILLINOIS, A CORPORATION OF ILLINOIS.

CASH-CARRIER.

SPECIFICATION forming part of Letters Patent No. 743,060, dated November 3, 1903.

Application filed March 23, 1903. Serial No. 149,069. (No model.)

To all whom it may concern:

Be it known that I, WILLIAM L. CHURCHILL, a citizen of the United States of America, residing at Chicago, in the county of Cook and State of Illinois, have invented certain new and useful Improvements in Cash-Carriers, of which the following is a specification.

My invention relates to certain new and useful improvements in cash-carriers; and its object is to produce a device of this class for use in connection with cable systems, and especially that type of cable system wherein the carriers are held in place upon the track by the engagement of a device extending downward from the carrier and underneath the rails.

To this end my invention consists in certain novel features of construction, which are clearly illustrated in the accompanying drawings and described in the specification.

In the aforesaid drawings, Figure 1 is a side elevation of my improved carrier, a portion of the box being broken away to show the interior construction. Fig. 2 is a bottom view of the carrier. Fig. 3 is a vertical cross-section in the broken line 3 3 of Fig. 5, showing a carrier as it is being placed in position upon the tracks. Fig. 4 is a section in the line 4 4 of Fig. 1, and Fig. 5 is a horizontal section in the line 5 5 of Fig. 1 looking downward.

Referring to the drawings, A A are two rails, (see Fig. 3,) preferably circular in cross-section, upon which the carrier runs, said rails being supported or suspended, as may be desired.

B is the box or carrier, which is preferably constructed of sheet metal in the manner which is clearly indicated in the drawings, and which is particularly described in my patent on cash-carriers, dated November 11, 1902, No. 713,059.

b represents the downwardly-extending lugs on the side of the box, which, as set forth in the prior patent above referred to, are adapted to extend downward and guide the carrier upon the track.

The bottom of the box B (indicated in the drawings by b') is made with upwardly-sloping lateral portions b², which are secured

within the folds of the lugs b in the same manner as is the bottom of the box of my prior patent, the difference being, however, that the sides of the bottom slope upward in the box of this carrier. Two ears b³ are stamped down from the bottom of the box at right angles thereto, and between these ears parallel to the length of the box run two shafts C. Upon each of these shafts is journaled one member D of a pair of combined cable-engaging jaws and track-engaging hooks. Each of the members D is preferably formed of a single sheet of metal and consists of a comparatively flat portion d, two ears d' stamped upward therefrom, a downwardly-extending cable-engaging hook d², a detent d³, a track-engaging hook d⁴, and a lug d⁵, stamped downward from the track-engaging hook. The members D are pivoted by means of the shafts C, as heretofore pointed out, these shafts passing through suitable perforations in the upwardly-extending ears d'. When the two members are thus positioned, each detent d³ extends over the top of the cable-engaging hooks d² of the other member, so as to cause the two members necessarily to swing upon their pivots at the same time. Springs E, surrounding the shafts C, hold the two members D normally in the position shown in Fig. 4, tending, therefore, to prevent the parts from assuming or maintaining the position shown in Fig. 3, wherein the track-engaging hooks d⁴ are raised and the cable-engaging jaws d² are separated. The plate F, of ebonite, such as is usually employed in cash-carriers, is secured to the bottom of the carrier to present the proper frictional surface to the tracks.

The operation of this much of the device will be readily apparent. When it is desired to start the carrier upon one of its trips, it is merely placed forcibly upon the rails. This raises the cable-engaging hooks d⁴ and spreads their ends apart, as shown in Fig. 3, permitting the cash-carrier to assume its proper position upon the rails. As the hooks are thus raised the cable-engaging jaws d² are swung apart to the position of Fig. 3, wherein they are in a position to grasp the cable. When the carrier is in position, the track-engaging

hooks d^4 slip back to their normal position outside of the rails, the cable-engaging jaws d^2 grasp the cable, and the carrier proceeds upon its journey.

5 A spring-pressed latch G is provided to lock the cover of the box (indicated by B') in its closed position. This latch G is provided with a downwardly-extending point g . A perforation d^6 is provided in one of the members D , through which this downwardly-extending point g passes when the members D are swung to the position shown in Fig. 3. The latch G is, however, so positioned that if the cover is shut, but not latched, so that 15 the latch does not reach its normal position the point g will engage with the solid body of the member D and prevent its being raised. In other words, if paper or something similar gets caught by the cover and the latch 20 does not, therefore, get a firm hold upon the cover the carrier cannot be placed upon the rails, because the track-engaging hooks cannot be raised and separated. Furthermore, when the cover is locked by the latch and the 25 carrier is placed upon the track and the cable grasped in the jaws it is impossible for the cover to become unlatched until the cable is released from the jaws, because of the fact that the portions d of the jaws are swung 30 upward slightly, thereby bringing the end of the slot d^6 immediately in front of the point g of the latch. This prevents any movement of the latch in a direction to release the cover. It will be readily apparent that this is an 35 important feature in cash-carriers and avoids any danger of the contents of the box being accidentally discharged. The lugs d^5 upon the hooks are intended to be engaged by suitable devices along the trackway to separate 40 the cable-engaging jaws at the delivery-stations in order to permit the carrier to stop at points other than the ends of the system.

I realize that considerable variations are possible in the details of this construction, 45 and therefore do not intend to limit myself to the specific form herein set forth except as pointed out in the claims.

I claim as new and desire to secure by Letters Patent—

50 1. The combination with a box, of a movable device extending downward from the box and under the rails, and cable-engaging jaws connected with said device, whereby the motion of said device as the box is placed upon 55 the tracks, will bring said jaws together upon the cable.

2. The combination with a box, of a movable device extending downward from the box and under the rails, and cable-engaging jaws 60 connected with said device, whereby the motion of said device as the box is placed upon the tracks, will separate said jaws and permit them to come together upon the cable.

3. The combination with a box, of two members pivoted to the box and extending downward therefrom and underneath the rails, and

cable-engaging jaws connected with said members and adapted to be brought together upon the cable when said members are moved in placing the box upon the tracks.

4. The combination with a box, of two members pivoted to the box and extending downward therefrom and underneath the rails, and cable-engaging jaws connected with said members and adapted to be separated and brought 75 together upon the cable when said members are moved in placing the box upon the tracks.

5. The combination with a box, of movable devices extending from the box on the two sides thereof and under the rails, said devices being in mutual engagement and only simultaneously movable, and cable-engaging jaws connected with said devices, and adapted to be brought together upon the cable by the movement of said devices as the box is placed 85 upon the rail.

6. The combination with a box, of track-engaging hooks pivoted thereto, cable-engaging jaws connected with said hooks and adapted to be brought together upon the cable, as the box is placed upon the tracks.

7. The combination with a box, of track-engaging hooks pivoted thereto, cable-engaging jaws connected with said hooks and adapted to be separated and brought together upon 95 the cable, as the box is placed upon the tracks.

8. The combination with a box, of track-engaging hooks pivoted thereto, and in engagement with one another so as to be simultaneously moved, and cable-engaging jaws 100 connected to said track-engaging hooks and adapted to be separated and brought together upon the cable when the box is placed upon the track.

9. The combination with a box, of cable-engaging hooks pivoted thereto, and in mutual engagement with one another, cable-engaging jaws integral with said track-engaging hooks, adapted to be separated and brought together upon the cable when the box is placed 110 upon the tracks.

10. The combination with a box and a cover thereon, of track-engaging hooks pivoted to the box, cable-engaging jaws connected to the track-engaging hooks and adapted to be 115 raised and brought together upon the cable when the box is placed upon the track, a latch adapted to hold the cover closed, and means whereby movement of the hooks and cable-engaging jaws is prevented when the cover 120 is imperfectly closed.

11. The combination with a box and a cover thereon, of track-engaging hooks pivoted to the box, cable-engaging jaws connected to the track-engaging hooks and adapted to be 125 raised and brought together upon the cable when the box is placed upon the track, a latch adapted to hold the cover closed, and a portion of said latch adapted to engage with said track-engaging hooks to prevent their movement when the cover is imperfectly closed.

12. The combination with a box, of cable-

engaging hooks pivoted thereto, a cover, a latch adapted to engage said cover to lock the same in place, having a portion adapted to engage one of the jaws when the jaws are in the position of grasping the cable, whereby accidental unlatching of the cover is prevented, substantially as described.

13. The combination with a box, of track-engaging hooks pivoted thereto, each of said hooks having a portion coacting with the hook, whereby movement of one of said hooks

will correspondingly move the other one, substantially as described.

In witness whereof I have signed the above application for Letters Patent at Chicago, in the county of Cook and State of Illinois, this 4th day of March, A. D. 1903.

WILLIAM L. CHURCHILL.
